UNITED STATES PATENT OFFICE.

STUART W. CRAMER, OF CHARLOTTE, NORTH CAROLINA.

DYEING APPARATUS.

No. 835,813.

Specification of Letters Patent.

Patented Nov. 13, 1906.

Application filed November 17, 1904. Serial No. 233,194.

To all whom it may concern:

Be it known that I, STUART W. CRAMER, a citizen of the United States, residing at Charlotte, in the county of Mecklenburg and 5 State of North Carolina, have invented certain new and useful Improvements in Dyeing Apparatus; and I do hereby declare the following to be a full, clear, and exact description of the invention, such as will enable others 10 skilled in the art to which it appertains to make and use the same.

My invention relates to the art of dyeing wool, cotton, or other material, has especial reference to improvements in the apparatus 15 or machinery for dyeing in vats, tanks, or other receptacles in which the material to be dyed is supported on a vertically-movable bottom supplemental to the bottom of the receptacle and is discharged therefrom by 20 elevating the supplemental bottom, as shown in my patent bearing date of July 26, 1904, and numbered 765,883.

The invention disclosed in said patent presented a machine or apparatus which permitted the duplication of shades of color in a 25 reasonable and satisfactory commercial degree of accuracy.

My present invention has for its object 30 more particularly improvements in the details of construction for securing uniform conditions in the individual batch or charge of material being treated.

Experience in operating this class of machines or apparatus has demonstrated that 35 the material to be dyed is generally loaded more or less unequally and that it is desirable to provide some elasticity in the construction of the apparatus that will automatically adjust the distances between the 40 top and bottom plates of the apparatus to compensate for said inequality of loading. This result is accomplished in my invention by providing an automatically tilting or yielding supplemental bottom connected by 45 a universal joint to the supporting-piston and also said supplemental bottom being partially supported upon springs sufficiently elastic to cause it to take a position out of the horizontal, thereby accommodating an un- 50 equally-distributed load and still maintaining as nearly as possible a uniform pressure on the load.

After most carefully loading the material to be treated it has been found that when the 55 usual flat cover has been placed and clamped down and the pump started to start the cir-

culation the liquor naturally finds its way up through the points of least resistance or where the material is thinnest. With a reasonable amount of care in loading this 60 will not amount to anything through the general body of the material; but all around the edges next to the walls of the tank or receptacle the dye liquor bubbles up with great force, often spouting several inches in height. 65 This the operatives endeavor to check by driving shingles down between the sides of the tank and the cover to compress and mat the material around the edge into a gasket or packing. To overcome this serious defect, I 70 provide an annular vertically-depend ing flange on the under side of and around the cover adjacent to the wall of the tank, which compresses the material around the edges of the cover, prevents the escape of the dye 75 liquor at this point, and compels the liquor in circulation to pass through and permeate the batch or charge of material and dye it uniformly. It is self-evident that if the liquor is allowed to pass through the main 80 body of the batch to be dyed in a slow and sluggish manner and to rapidly circulate through it in other thin places the result will be an unequally-dyed batch.

By my improved construction the batch 85 or charge is maintained under an approxi- mately even degree of pressure throughout the area of the receptacle, and a consequent even dyeing of the material is accomplished in each individual batch treated, and the 90 batch may be duplicated as many times as it is desired to produce the same shade of color.

Another serious obstacle encountered in 95 operating this class of apparatus lies in handling the wet stock or material for unloading the tank or receptacle. In some classes of apparatus where the material is hoisted out of the tank the wet stock clings to the chains connected to the cover, and at best the removal when effected by hand is laborious 100 and exceedingly difficult. To overcome this, it is my purpose to provide mechanical appliances to remove the dyed material from the supplemental bottom after it has been 105 expelled from the receptacle.

The invention will be fully disclosed in the following specification and claims.

In the accompanying drawings, which 110 form part of this specification, Figure 1 is a side elevation, partly in section, illustrating my invention; and Fig. 2, a vertical trans- verse section, partly in side elevation, of a

tank or receptacle provided with my improvements on an enlarged scale.

Reference being had to the drawings and the designating characters thereon, 1 indicates a tank, vat, or other receptacle in which the material is treated; 2, a perforated or foraminous cover provided with a vertical flange 3, extending from the under side of the cover and adjacent to the wall of the receptacle with which the material engages and forms a packing-gasket to prevent the liquor rising around the edge of the cover and with a like flange 3' on the upper side of the cover. The cover is secured in the receptacle by suitable clamps pivotally secured to the wall of the receptacle, and distributed around the upper end of the receptacle in such number as may be required. One clamp is shown at 4.

5 indicates a perforated or foraminous supplemental bottom, also provided with a vertical flange 6 on the under side thereof, and is connected to the piston 7 of a hydraulic cylinder 8 by a universal joint 9 to enable the bottom to tilt automatically under unequal distribution of the batch or charge of the material, and under the bottom, secured to the upper end of the piston 7 adjacent to the universal joint, is a spider 10, having radial arms 11, on which are springs 12, secured in position by pins 13, to take the weight of the load on the bottom 5 and adjust the bottom to maintain a horizontal plane in the receptacle as the bottom is raised to express liquid from the charge or batch thereon or to expel the charge from the receptacle. These springs also compensate for any inequalities in the distribution of the charge and secure an equal distribution of pressure on and consequent equal density of the charge. The bottom 15 of the tank or receptacle is provided with a stuffing-box 16, through which the piston 7 passes, and on the upper end of the cylinder 8 is a like stuffing-box 17.

18 indicates a liquid-supply pipe communicating with a pump 19 and discharges into an annular cap 20, having a lateral outlet 21, and the liquid is drawn off from the receptacle through a pipe 22 and returned to the source of supply in the usual manner. On the wall 50 of the receptacle and at the upper end thereof are pockets 23, only one of which is shown, to receive the overflow of the liquid discharged through slots 24 in the wall of the receptacle and returned to the pump through pipes 25 and 26 to be again circulated through the charge in the receptacle.

27 indicates a hydraulic cylinder supported in horizontal position at one end on a bracket 28, secured to the wall of the receptacle, and 60 at the opposite end on a stanchion 29 and is provided with a piston 30, on whose outer end is a concavo-convex head 31, the radius of whose inner or convex face is approximately the same as the radius of the inner 65 surface of the wall of the receptacle to engage

the compressed batch or charge after it has been expelled from the receptacle and remove it laterally from the supplemental bottom 5 when it falls upon a truck or the floor 32 outside the receptacle 1. The cylinder 27 70 is provided with a stuffing-box 33, and the piston is restored to its normal position by a counterweight 30'. The bore of the cylinders 8 and 27 is in excess of the diameter of their respective pistons 7 and 30, and the cylinders 75 are supplied with water from a pump 34, respectively, through pipes 35 and 36, through which the water from the cylinders is discharged in the usual manner of operating hydraulic engines. 80

37 indicates a track or trolley on which is suspended a right and left hand screw-threaded rod 38, made in two parts, which engage an elongated hub 39 of a hand-wheel 40 for raising the cover 2 out of the receptacle and moving it out of the way to load or charge and unload or discharge the material to and from the receptacle. The liquid in the tank or receptacle may be maintained at any desired temperature by steam supplied through a coiled pipe 41 and discharge through pipe 42. 85

It is obvious that this apparatus may also be used for boiling, washing, or bleaching purposes without departing from the spirit 95 of my invention and that changes in the details of construction may also be made.

Having thus fully described my invention, what I claim is—

1. A receptacle provided with a removable 100 foraminous cover, a reciprocatory and automatically-tilting foraminous supplemental bottom yieldingly supported, means for supplying liquid to the receptacle, and means for withdrawing the liquid. 105

2. A receptacle provided with a removable cover, a reciprocatory and automatically-tilting supplemental bottom, a yielding support under said bottom, means for supplying liquid to the receptacle, and means for withdrawing the liquid. 110

3. A receptacle having an open upper end, a removable cover secured therein, a supplemental bottom vertically movable in the receptacle, means adapted to permit automatic movement of the bottom to compensate for inequalities in the distribution of the charge on said bottom and maintain an approximately even degree of pressure on the charge. 115 120

4. A receptacle provided with a removable cover, a supplemental bottom on which material to be treated is supported, means for raising the supplemental bottom and expelling the material from the receptacle, and 125 means for removing said material from the supplemental bottom.

5. A receptacle provided with a removable cover, a supplemental bottom on which material to be treated is supported, means for 130

raising the supplemental bottom and expelling the material from the receptacle, and means for removing said material laterally from the supplemental bottom.

5 6. A receptacle provided with a removable cover, a supplemental bottom on which material to be treated is supported, means for raising said bottom to the upper end of the receptacle, and means for removing the material bodily and laterally from the supplemental bottom.

7. A receptacle provided with an open upper end, a removable cover secured therein, a supplemental bottom, a motor for raising 15 said bottom, a universal joint connecting the bottom to the motor, means for supplying liquid to the receptacle, and means for withdrawing the liquid.

8. A receptacle provided with an open upper end, a removable cover secured therein, a 20

supplemental bottom, means for raising said bottom, a universal joint under said bottom, springs under said bottom, means for supplying liquid to the receptacle, and means for withdrawing the liquid.

9. A receptacle provided with a removable cover, a reciprocatory supplemental bottom provided with means for automatically adjusting said bottom under unequally-distributed loads and thereby maintaining approximately uniform pressure on the load, means for supplying liquid to the receptacle, and means for withdrawing the liquid.

In testimony whereof I affix my signature in presence of two witnesses.

STUART W. CRAMER.
